(57) **CLAIM**

The ornamental design for a mattress cover, as shown and described.

DESCRIPTION

FIG. 1 is a first perspective view of a mattress cover design; FIG. 2 is a front elevational view of the mattress cover design of FIG. 1;

FIG. 3 is a rear elevational view of the mattress cover design of FIG. 1;

FIG. 4 is a right side elevational view of the mattress cover design of FIG. 1;

FIG. 5 is a left side elevational view of the mattress cover design of FIG. 1;

FIG. 6 is a top view of the mattress cover design of FIG. 1; and,

FIG. 7 is a bottom view of the mattress cover design of FIG. 1.

The broken line disclosure represents unclaimed portions of the mattress cover in which the design is embodied.

1 Claim, 5 Drawing Sheets
